UNITED STATES PATENT OFFICE.

JOHN E. LITTLE, OF PRINCETON, INDIANA.

GATE.

SPECIFICATION forming part of Letters Patent No. 408,117, dated July 30, 1889.

Application filed March 19, 1889. Serial No. 303,836. (No model.)

To all whom it may concern:

Be it known that I, JOHN E. LITTLE, a citizen of the United States, residing at Princeton, in the county of Gibson and State of Indiana, have invented certain new and useful Improvements in Gates, of which the following is a specification, reference being had therein to the accompanying drawings, in which—

10 Figure 1 represents a perspective view of my improved gate closed, a portion of one of the operating-levers being broken off; Fig. 2, a plan view of the same, the position of the gate and operating-levers when open being indicated by dotted lines; and Fig. 3, a perspective view of the gate, showing a slight modification of the operating-bars.

The invention has for its object, essentially, the production of an extremely simple and 20 practical swinging gate of that class adapted to be opened without alighting from the vehicle, as will be more fully hereinafter specified.

Referring to the drawings annexed, A A' 25 designate, respectively, the main or hinge post and the supplemental or latch post, and B the gate, which may be of any construction, and is hinged to the post A in any suitable manner. The gate is provided with a sliding latch-bar a, which rests upon the upper edge of one of the gate-rails and works between the vertical battens of the gate, a transverse pin a' being inserted in the bar to restrict its movement when drawn back. 35 When the latch is pushed forward, its forward end enters a recess in the adjacent face of the latch-post in the usual manner, and locks the gate.

Planted or anchored in the ground a suitable distance from the main post A, and in line therewith, is a supplemental post C. These two posts support a horizontally-reciprocating bar D, which is held in recesses in the sides of the post by means of plates or 45 boards b. This bar D is operated by means of two horizontal bars or links E E, whose inner or adjacent ends are pivoted upon the face of a block c, affixed to the said bar D about midway its length. The other ends of 50 the links E are pivotally connected to the lower ends of the vertical bars of the angle-levers F F, these angle-levers being pivoted,

respectively, upon the posts A C. The horizontal bars of the angle-levers are extended out in the line of the roadway a suitable distance and provided with depending operating rods or handles G. The operating-handle and a portion of the angle-lever to the right of the figures are broken away, as is evident.

Pivoted or hinged to the post A is a horizontal arm H, the outer end of which is connected to the latch-bar a by means of a link d. This arm H is also connected to the reciprocating bar D by means of a link e, which is pivoted to the top of the bar D and the bottom of the arm H at suitable points. The arm H and link e, it will be observed, form a sort of toggle-lever connection between the main post and the bar D.

In the modification shown in Fig. 3 the connecting-bars E are done away with, and the angle-levers connected directly to the sliding bar, and the sliding bar is disengaged from the posts and allowed to swing freely back and forth without the slightest friction.

The operation of the gate is as follows: A quick downward pull upon the left-hand one of the operating-handles G will impart a forward movement to the bar D, which, through the medium of the links and arm, will unlatch the gate and swing it a little more than halfway open, in which position the arm H and link e will be on the outside of the reciprocating bar D. Then, by a sudden upward push upon the same operating-handle the gate may be swung completely open, the position of the gate and bars and links while the gate is open being shown in dotted lines in Fig. 2. The operation of closing the gate is precisely the same as in opening—that is to say, a sudden downward pull is first given the operating-handle and then it is pushed upward, the gate being automatically latched. In operating the gate from the other handle G—that is, the one to the right, which is not shown on the drawings—the operation is reversed—that is, the handle is first pushed up and then pulled down, as is evident.

It is evident that I can vary the construction somewhat without departing from the spirit of the invention.

Having thus fully described my invention, what I claim is—

1. The combination of a gate and posts, a

reciprocating bar mounted upon these posts, suitable operating-levers connected to this bar, an arm H, pivoted to one of the posts, and pivotal links connecting this arm to the 5 gate and bar, substantially as described.

2. The combination of a gate and suitable posts, a reciprocating bar and operating-levers, a latch-bar on the gate, an arm H, pivoted to one of the posts and connected to 10 this latch-bar by means of a link, and a

pivotal link connecting this arm to the reciprocating bar, substantially as and for the purpose set forth.

In testimony whereof I affix my signature in presence of two witnesses.

JOHN E. LITTLE.
